SPRING WINDER

Jesse A. Gates, Royal Oak, Mich.

Application January 13, 1945, Serial No. 572,705

2 Claims. (Cl. 140—124)

1

This invention relates to spring winders and has for its principal object the provision of a device of this type that is simple in construction, efficient in operation, and economical to build.

Objects of the invention include the provision of a spring winder comprising a pair of U-shaped members arranged in nesting relationship, the overlapping sides or legs of the members being provided with openings therein for reception of a spring winding mandrel, means cooperating between the members to cause the mandrel to be frictionally gripped between the members, means being provided for rotating the mandrel, and means being provided for directing the path of travel of spring wire onto the mandrel at any desired angle so as to enable a spring having the desired pitch of its convolutions to be wound thereby; the provision of a device of the type described in which the mandrel receiving openings in one of the U-shaped members each includes a V-notch directed in one direction with respect to the path of relative movement between the members and the mandrel receiving openings in the other members each includes a V-notch directed oppositely to the V-notches in the first-mentioned member; the provision of a construction as above described in which screw means cooperate between the bottoms of U-shaped members to control the relative movement between them and, therefore, the amount of frictional resistance to the turning of a mandrel received between the members; the provision of a construction as above described in which a novel form of wire guide is provided for directing the wire at desired angles onto the winding mandrel; the provision of a construction as above described in which the wire guiding member is arranged to permit friction to be applied to the wire passing therethrough whereby to control the tightness with which the wire is wound on the mandrel; the provision of a construction as above described in which the wire guide is so positioned with respect to one of the members as to maintain a minimum distance between it and the mandrel regardless of the size of the mandrel employed; the provision of a device of the type described in which the wire guide is freely adjustable during the winding of a wire upon the mandrel whereby to enable a spring wound thereby to be provided with square ends; and the provision of a device of the type

2

described in which the openings in the member for receiving the mandrel is capable of receiving a variety of different sizes of mandrels whereby springs of different diameters can be wound by the device.

The above being among the objects of the present invention, the same consists in certain novel details of construction and combinations of parts to be hereinafter described with reference to the accompanying drawing, and then claimed, having the above and other objects in view.

In the accompanying drawing which illustrates a suitable embodiment of the present invention and in which like numerals refer to like parts 15 throughout the several different views,

Fig. 1 is a partially broken, side elevational view of the device of the present invention illustrating a helical spring being wound thereon;

Fig. 2 is an enlarged, transverse sectional view 20 taken on the line 2—2 of Fig. 1;

Fig. 3 is an enlarged, fragmentary transverse sectional view taken on the line 3—3 of Fig. 1;

Fig. 4 is a fragmentary sectional view taken axially of the winding mandrel, as on the line 4—4 25 of Fig. 3 illustrating the arrangement of parts for winding a spring of the closed coil type; and,

Fig. 5 is a view similar to Fig. 4 but illustrating the arrangement of parts when winding a coil spring of the open coil type.

Referring to the drawing and particularly to Fig. 1 it will be noted that the device of the present invention comprises a pair of U-shaped metallic members 10 and 12, respectively, the sides of each of which are arranged in parallelism to each other. The member 10 is deeper than the member 12 and it is sufficiently wider than the member 12 so as to receive the latter between its sides in slidably contacting relation with respect thereto. The members 10 and 12 may be conveniently formed from strip metal and preferably steel inasmuch as in the latter case they may be hardened so as better to resist wear, or at least the portions provided with the openings hereinafter referred to may be hardened for this purpose.

The side arms 10 adjacent their outer free ends are each provided with a hole 14, best brought out in Fig. 3, centrally of the width thereof, the holes 14 in both arms being aligned with one another. As best brought out in Fig. 3 the holes

14 are of generally circular conformation over their lower portions and are formed to provide a V 16 on their outer sides directed centrally toward the free ends of the sides of the member 10. Likewise the side arms of the member 12 are each formed to provide an opening 18 therein of the same size and shape as the openings 14 but in this case with the V portion 20 thereof directed toward the bottom of the member 12, or in opposition to the V 16 of the members 14. This arrangement of the V's of the openings 14 and 18 is that employed for frictionally gripping the winding mandrel when the direction of force setting up such friction is that tending to urge the inner member 12 outwardly of the member 10 as will be more fully appreciated from the following description. As will also be appreciated, if the direction of force applied between the members 10 and 12 to apply frictional resistance in turning of the mandrel is desired in the opposite direction, that is in a direction to pull the member 12 downwardly into the member 10, then the direction of the V's in both members 10 and 12 will be reversed from that shown. It will also be appreciated from the following description that the V's in that one of the members 10 or 12 which is urged outwardly with respect to the other to frictionally grip the mandrel may open out through the ends of the arms or sides of such member instead of forming a part of the openings as shown, and reference hereinafter in the specification and claims to the arms or sides of the members 10 and 12 as having holes provided with such V's is to be interpreted accordingly.

The openings 14 and 18 are adapted to receive therethrough a wire winding mandrel such as 22 upon which the desired coil of wire is to be wound. Various diameters of mandrels 22 may be employed up to the capacity of the holes 14 and 18 as will readily be appreciated. It may be stated as a matter of explanation that with a device of the type shown having holes 14 and 18 of a size capable of receiving a mandrel up to one-half inch in diameter, mandrels as small as $\frac{1}{2}$ of an inch in diameter have been employed and wire of the same diameter as the mandrel tightly wound thereon to form a spring.

The mandrel 22 or its equivalent is in practice frictionally gripped between the V's 16 and 20 of the corresponding sets of arms of the members 10 and 12, it being understood that the amount of friction thus applied to the mandrel in any particular case will preferably be sufficiently great to prevent reverse direction of rotation of the mandrel during a spring winding operation under the tension built up in the spring wire being wound should the turning force on the mandrel be relieved. While in the broader aspects of the present invention any suitable means or mechanism may be applied in cooperating relation between the members 10 and 12 to permit adjustment of the position of the latter within the former, and to apply a gripping force on a mandrel such as 22 received in the respective openings 14 and 18 of such members, the particular means shown appears to be about as simple and economical as any. This comprises a screw 24 which is threaded upwardly through a boss 26 fixed to the member 10 centrally between the side arms thereof and which screw extends up to the member 12 and is there reduced in diameter as at 28 to form a shoulder which abuts against the lower face of the member 12. The reduced end 28 projects up through the member 12 in freely rotatable relation with respect there-

to and above the member 12 is headed over as at 28, so that threading of the screw upwardly or downwardly in the boss 26 will cause a corresponding positive movement of the member 12 with respect to the member 10.

Any suitable means may be provided for rotating the mandrel 22 but inasmuch as mandrels of different diameters will be employed in connection with the device such turning means 10 should be capable of being adapted to all the various sizes of mandrels capable of being received by the device. The handle 30 shown provided for the purpose of turning the mandrel 22 includes an enlarged hub portion 32 which as best brought out in Fig. 2 is provided with an opening 34 therein of somewhat the same nature as the openings 14 and 18 in the members 10 and 12 and previously described. In other words, the opening 34 is generally cylindrical but is provided with a V surface 36 at one side thereof adapted to receive an end of the mandrel 22. A set screw 38 is threaded radially of the hole 34 in alignment with the center line of the V 36 and is employed for clamping the ends of the mandrel against the sides of the V 36. Preferably the corresponding end of the mandrel is flattened off as indicated best in Fig. 2 to provide a seat for the inner end of the set screw 38 and thereby aid in preventing relative turning of the handle 30 and the mandrel 22. It will be noted that the hub portion 32 of the handle 30 on its inner face is provided with an axially projecting knob or headed pin 40 the purpose of which will be presently described.

35 In order to guide the wire upon the mandrel 22 during a winding operation the following mechanism is provided. It will be appreciated from the following description that broadly this guiding mechanism may be provided in any position around the opening 14 at the corresponding end of the member 10, but in accordance with one phase of the present invention is preferably provided opposite the point of the V 16 of such opening, this regardless of whether the 40 point of the V is at the top or the bottom and previously explained. In the particular embodiment shown, the point of the V being directed upwardly, the guiding device is, therefore, positioned over the corresponding V 16 for the corresponding opening 14, shown in the drawings as that one thereof at the righthand end of the device as viewed in Fig. 1. This guiding device 45 comprises an outwardly projecting partially cylindrical boss 42 rigidly fixed to the outer face 50 of the righthand arm or side of the channel member 10 immediately above the point of the V 16 of the corresponding opening 14. It is provided with a horizontally directed bore 44 therethrough the axis of which is in parallelism with the plane 55 of thickness of the corresponding side of the member 10. Immediately above the point of the V the boss 42 is vertically slotted as at 46 preferably substantially completely through the bore as best brought out in Figs. 4 and 5. Rotatably received within the bore 44 of the boss 42 is the 60 end of an L-shaped member 48 and the outer extremity of that portion of the member 48 received within the bore 44 is diametrically slotted as at 50.

65 In making a helical wire spring by the use of the device of the present invention a mandrel such as 22 is first selected of a diameter equal to, or slightly smaller than, the desired bore of the spring to be wound. The handle 30 is secured to one end thereof and then the mandrel 70

is projected through the holes 14 and 18 of the members 10 and 12 to a position in which the hub 32 of the handle 30 is in relatively close relation with respect to the boss 42 on the member 10. The screw 24 is then tightened up until the desired amount of frictional resistance to rotation is created by the V's 16 and 20 on the mandrel 22. Preferably the device is then placed in a vise so as to provide a means for holding the members 10 and 12 stationary during the spring winding operation. A piece of wire such as 60 of the desired diameter is then projected down through the slot 46 of the boss 42 and through the slot 50 of the guide member 48 and its free end is then hooked about the knob 40. The guide member 48 is then rotated in the bore 44 of the boss 42 until the slot 50 thereof is arranged to direct the wire 60 at the desired angle onto the mandrel 22. The mandrel is then rotated by means of the handle 30, causing the wire to be wound upon it and the mandrel 22 to be forced axially with respect to the members 10 and 12 as the wire is wound upon the mandrel to form the spring. In case there is not sufficient drag on the wire 60 in passing through the slots 46 and 50 to cause the wire 60 to tightly hug the mandrel 22 during the winding operation, the operator may simply press the guide member 48 axially of the bore with his hand or finger so as to bind the wire 60 between the lefthand face of the slot 46, as viewed in Fig. 3, and the blind end of the slot 50 in the guide member 48, thus setting up enough friction so as to remedy this defect so that the final diameter of the bore of the spring being wound will be substantially equal to the diameter of the mandrel 22 being employed.

It will be appreciated that where an open coil spring is desired, that is of the type illustrated in Fig. 5, then the guide member 48 is turned in the boss 42 to such position that the slot 50 therein directs the wire 60 onto the mandrel 22 at such angle that the adjacent turns of the spring being formed will be spaced axially from one another by the desired distance. It will also be appreciated that the amount which the guide member 48 is turned to thus direct the wire 60 upon the mandrel 22 will govern the axial spacing between adjacent turns of the spring being formed.

Where a closed coil type of spring is desired then the guide member 48 may be rotated in the boss 42 so that the plane of the slot 50 therein is perpendicular to the axis of rotation of the mandrel 22, or slightly to one side of such plane, so as to eliminate any spacing between the coils of the spring being formed. On the other hand, and as brought out in Figs. 1 and 4 it is possible with this device to wind a closed coil type of spring in which the turns are tensioned toward one another so that a greatly increased amount of force is required to separate the coils as compared to the same type of spring where the coils are merely wound into contact with one another without such tension. In forming this last-mentioned type of spring the guide member 48 is turned to the relative position illustrated in Figs. 1 and 4, to the opposite side of a plane perpendicular to the axis of the mandrel 22 and passing through the axis of the bore 44 from the normal position of the guide member when winding an open coil type of spring as shown in Fig. 5. In this case the wire in being fed onto the mandrel 22 attempts to ride over the turn previously made but where the resistance to the feed of the wire through the guiding device is sufficiently great,

and which may be controlled as previously described, it is forced into direct contact with the mandrel and although the angularity is the reverse of that normally required to cause the mandrel to feed outwardly, or to the right as viewed in Fig. 1 during the winding of the spring thereon, the wire in being coiled builds up between the portion of the coil already formed and the opposed face of the member 10 and causes the mandrel to be forced axially outwardly as in the case of winding a conventional type of spring.

One feature of the present invention which is of advantage particularly in winding up an open coil type of spring as illustrated in Fig. 5, by reason of the fact that the guide member 48 is adjustable by the operator during a winding operation, is that in starting to wind up the spring the guide member 48 may be positioned to form a square turn on the first end being wound, then shifted as, for instance, to the position shown in Fig. 5 to obtain the desired spacing of the coils, and when the proper length of the spring has been wound then shifted again to form a square end on the final end of the spring. Thus by simply controlling the position of the guide member 48 during the winding of the spring the operator may in one operation obtain a spring in which the end turns are square with the axis of the spring, as is often desirable, thus eliminating the added operation which would otherwise be necessary to provide such square end.

Having thus described my invention, what I claim by Letters Patent is:

- 35 1. In a spring winder, in combination, a pair of U-shaped members one received in nested relation within the other and slidably with respect thereto, the sides of each of said members each being provided with a V, both V's of each of said members being directed in the same relative direction of movement between said members and the V's of one member being directed oppositely to the V's of the other of said members, said V's being adapted to receive a mandrel, means for effecting relative movement between said members whereby to cause such mandrel to be frictionally clamped by the opposed V's of said members, a boss fixed to the outer of said members and to the outer face of one of the sides thereof in closely adjacent relationship with respect to said V therein, said boss having a bore therein arranged with its axis in a plane transverse to the axis of said mandrel and having a slot extending therethrough into said bore in a plane transverse to the axis of said bore, and an axially slotted wire guide member rotatably received within said bore, the slot in said guide member extending into intersecting relationship with respect to said slot in said boss.
- 40 2. In a spring winder, in combination, a pair of U-shaped members one received in nested relation within the other and slidably with respect thereto, the sides of each of said members each being provided with a V, both V's of each of said members being directed in the same relative direction of movement between said members and the V's on one member being directed oppositely to the V's of the other of said members, said V's being adapted to receive a mandrel, means for effecting relative movement between said members whereby to cause such mandrel to be frictionally clamped by the opposed V's of said members, a boss fixed to the outer face of the side of the outer of said members in closely adjacent relationship with respect to the point
